Assistant Examiner — Caitlin A Laverty

CLAIM

I claim the ornamental design for a remote control device for a vehicle, as shown and described.

DESCRIPTION

FIG. 1 is a front elevational view of a remote control device for a vehicle showing my new design;

FIG. 2 is a back elevational view thereof;

FIG. 3 is a left side elevational view thereof; wherein an omitted right side elevational view thereof is identical with the left side elevational view;

FIG. 4 is a top plan view thereof;

FIG. 5 is a bottom plan view thereof; and,

FIG. 6 is a perspective view thereof.

1 Claim, 4 Drawing Sheets
